HARRY A. HIGGINS, OF DETROIT, MICHIGAN, ASSIGNOR TO LONG MANUFACTURING COMPANY, OF DETROIT, MICHIGAN, A CORPORATION OF MICHIGAN

FIN CONSTRUCTION

Application filed December 13, 1926. Serial No. 154,552.

The invention relates to radiators which are particularly adapted for cooling the water of internal combustion engines in motor vehicles. The main object of the invention is to provide an improved construction of radiator fin to secure more efficient cooling. Another object is to provide a fin construction which may be economically manufactured. With these as well as other objects in view, the invention resides in the novel features of construction and combinations and arrangements of parts as more fully hereinafter set forth.

In the drawings:

Figure 1 is a front elevation of the core of a radiator embodying my invention;

Figure 2 is an enlarged fragmentary horizontal cross section therethrough;

Figures 3 and 4 are cross sections on the lines 3—3 and 4—4, respectively, of Figure 2.

The core of the radiator in the present instance comprises the upper and lower headers 1 and 2, respectively, the vertical cylindrical water tubes 3 extending between the headers, and the series of horizontal heat radiating fins 4, through which the tubes pass in heat conducting contact therewith. The tubes 3 are arranged in a series of rows 3', 3'', 3'', 3'', etc., each of which takes a zig zag path. The fins 4 extend transversely of the tubes between the opposite sides and the front and rear of the radiator and are vertically spaced from each other to form with the tubes a series of air passageways. These fins are preferably formed of sheet metal strips having upwardly extending annular flanges 5 surrounding the openings through which the tubes pass and arranged in heat conducting contact with the tubes.

For the purpose of securing more efficient cooling or, in other words, greater cooling effect per pound of metal, the fins are formed with the series of openings 6 intermediate the openings through which the tubes extend and also with an integral raised projection 7 at the rear edge of each opening 6, both the openings and projections being preferably formed by a stamping operation. Each projection 7 is raised slightly above the main portion of its fin and is inclined rearwardly and

downwardly and is also preferably tapered rearwardly to form on the under side of the fin a rearwardly tapering shallow recess. With this arrangement, air passing through the passageways between the fins and tubes is cut by the projections and a part thereof is directed downwardly through the openings from the upper sides of the fins to and along the lower sides of their fins and another part thereof is induced to flow along the upper sides of the fins. As a consequence, the heated stream of air immediately adjacent the fins is displaced by colder air and the heat is more readily dissipated.

What I claim as my invention is:

In a radiator, the combination with a plurality of spaced rows of water tubes extending from the front to the rear of the radiator, the tubes of each row being arranged in a serpentine path to define tortuous air passageways between adjacent rows, of heat radiating fins extending transversely of and in heat conducting contact with said tubes, said fins being provided with openings between the rows of tubes and rearwardly tapering inclined projections at the rear edges of the openings forming passages on the underside of the fins, the said passages having their inlet ends above the fins and facing in a direction opposite to the flow of air through the radiator adjacent the periphery of the respective openings, and their outlet ends on the underside of the fins and spaced rearwardly of the respective openings to direct air passing between said fins through the openings from one side of the fins to the other.

In testimony whereof I affix my signature.

HARRY A. HIGGINS.
